CLAIM

The ornamental design for a side panel bag, as shown and described.

DESCRIPTION

FIG. 1 is a front elevational view a side panel bag showing my new design;

FIG. 2 is a right side elevational view, the left side being identical thereof;

FIG. 3 is a top plan view thereof;

FIG. 4 is a bottom plan view thereof;

FIG. 5 is right side elevational view in the open position, the left side being identical thereof; and,

FIG. 6 is a top plan view in the open position thereof.

The broken line showing of a snap, and ring supports, in FIG. 6, is for illustrative purposes only and forms no part of the claimed design.
